Specification for Design.

Patented Mar. 7, 1922.

Application filed May 31, 1921. Serial No. 473,912. Term of patent 14 years.

To all whom it may concern:

Be it known that I, FREDERICK G. GRUEN, a citizen of the United States of America, and a resident of Cincinnati, in the county of Hamilton and State of Ohio, have invented a new, original, and ornamental Design for a Wrist-Watch Case, of which the following is a specification, reference being had to the accompanying drawing, forming part thereof.

The figure is a perspective view of a wrist-watch case embodying my new design.

I claim:

The ornamental design for a wrist-watch case, as shown.

FREDERICK G. GRUEN.
